UNITED STATES PATENT OFFICE.

ELIHU C. WILSON, OF LOS ANGELES, CALIFORNIA.

PIPE-SUPPORTING CLAMP.

Application filed October 22, 1924. Serial No. 745,167.

This invention relates to tools for handling well pipe and casing, and is more particularly concerned with devices for suspending or supporting drill pipes and casing from 5 rotary tables and the like. While not so limited in its application, I will describe the invention as used in connection with the suspension of drill stem during well drilling operations as carried on by the rotary 10 method. From this description it will be apparent to those skilled in the art, how the device may be employed in other situations.

The device is adapted to be supported on a rotary table, or other type of supporting 15 platform, and to be moved bodily thereover into and out of association with the drill pipe. Generally described, the device is in the nature of hingedly joined members having upwardly facing shoulders, said members, when the device is operatively associated 20 with the drill pipe, being adapted to be clamped together about the pipe with their upwardly facing shoulders in supporting engagement with downwardly facing pipe 25 shoulders.

Since the device is adapted to be slid over the table to and from operative association with the pipe, and to function solely as pipe supporting means rather than being used 30 alternately as a pipe support and elevator (as is true of devices used in connection with the well known "two-elevator system") it is necessary that there be two downwardly facing and vertically spaced shoulders on the 35 pipe. The upper shoulder is to take the hoisting elevator and the lower shoulder takes the supporting device. A tool joint embodying these shoulder characteristics is described in my copending application on 40 "well pipe joint," filed October 22nd 1924, Serial Number 745,168, and in that application I have explained the advantages of using a supporting clamp in connection with an individual supporting shoulder over the 45 use of wedge slips or the use of two elevators alternately used as supporting members and elevators when but a single downwardly facing shoulder is provided at each break-joint of the pipe.

50 In that application I have stated that any suitably shouldered type of clamp may be

used as a supporting member, for instance, an ordinary pipe elevator (with hoisting links detached) lends itself peculiarly well to the purpose. However, these elevators 55 and, in fact, any device of sufficient size to handle the work must be of very considerable weight and it is naturally a matter of some difficulty and a time-consuming operation to manipulate them.

60 Therefore, it is among the objects of the present invention to provide a supporting clamp which may be manipulated with comparative ease and speed, the aggregate time and labor saved by its use representing a 65 real factor in the ultimate cost and time consumed in drilling, and it is well understood that seconds saved at certain stages of drilling may mean the difference between a satisfactory or unsatisfactory hole.

70 The hinged members have extension handles whereby the operator, without getting into an awkward position, may swing them to and from closed position about the pipe, the same handles being used for bodily 75 shifting the device clear of the pipe or into association therewith when the members are spread apart. Preferably, there are one or more rollers on the device so the operator may easily roll the clamp over the table. 80 The roller is preferably so arranged that it is clear of the table when the clamp is supporting the pipe, but when the members are clear of the pipe the handles may be lifted to move the roller onto the table, whereupon the 85 clamps may be rolled (much after the manner of a wheel-barrow) about the table.

In order that the members may be releasably locked about the pipe to eliminate all 90 danger that they be accidentally knocked out of pipe supporting position, I preferably provide latch means on the clamp. The means employed are of a nature to resist accidental release under operating conditions or under strains that are at any time imposed 95 on the clamp.

In order that the latch may be easily released when occasion arises therefor, I provide means controllable from one of the handles whereby the operator may open the 100 latch without taking his hand from said handle. Thus a single operator may, with

comparative speed and ease, apply and disengage the clamp.

Other novel features and objects of the invention will be set forth in the following 5 detailed description, reference being had to the accompanying drawings, in which:

Fig. 1 is a side elevation partly in broken away section of my improved clamp showing it applied to a drill pipe and in connection 10 with a conventionally illustrated rotary table;

Fig. 2 is an enlarged side elevation of the clamp, one of the handles being broken away;

Fig. 3 is a plan view of Fig. 2, showing in dotted lines, the supporting members spread apart;

Fig. 4 is a section on line 4—4 of Fig. 2; and

Fig. 5 is a fragmentary view of Fig. 2, looking from the right thereof, and showing a preferred form of latch.

In Fig. 1 a usual rotary table is indicated at 10, and the upper end of a drill pipe at 11. 25 In its broader sense, rotary table 10 may be considered a supporting platform through which pipe 11 extends. Supported on table 10 is my improved clamp A, which embodies two arcuate, complementary supporting members 12 and 13 connected by the vertical hinge pin 14 so they may be horizontally spread apart to clear or closed to embrace pipe 11. Extension handles 15 and 16, on members 12 and 13, respectively, provide 30 means whereby the members may be easily swung open and closed without requiring the operator to closely approach pipe 11 or to assume an awkward position. The length of the handles also gives the operator advantage of considerable leverage.

When members 12 and 13 are closed, they need not fit snugly about the pipe as there is no necessity for the pipe to be tightly clamped between said members. In Fig. 1, I 45 have shown a comparatively large amount of clearance between the defining walls of bore B and the peripheral face of pipe 11. It is only necessary that the upwardly facing support shoulders 17 on the members 50 have ample bearing engagement with the downwardly facing support shoulder 18 on tool joint C, which joint is threadedly connected to the upper end of pipe 11. Joint C has a second downwardly facing shoulder 55 19, but the vertical spacing between shoulders 18 and 19 is such that a hoisting elevator D may be attached to the joint between the shoulders and engage shoulder 19 for the purpose of raising or lowering pipe 11. 60 With the clamp in the position of Fig. 1, pipe 11 and the entire weight of the string below is supported on shoulders 17, so elevator D may be detached from joint C for picking up a new stand E for attachment to 65 the string.

In order to hold members 12 and 13 in locked condition, I have provided a latch device therebetween. While this latch device may be of any suitable type, I have illustrated a form which is particularly well suited to the purpose. Shank 20 has a transversely extending head 21 on one end, while its other end is secured to vertical pivot shaft 22, said shaft being mounted in lugs 23 on member 13. The latch is provided 70 with spring 24 which tends at all times to urge the latch to its closed position.

On the free swinging end of member 12 are two vertically spaced latch lugs 27. During the closing of the clamp, latch head 21 rides over the forwardly curved faces 27a of lugs 27 and seats behind said lugs to resist opening movement of the members. Spring 24 first yielding to allow the latch to thus ride over the lugs and then yieldingly holding the latch in locking association with the lugs.

In order that the latch may be easily released by the operator, I prefer to extend a pull rod 28 from eye 29 on shank 20 to a bell crank actuating handle 30 pivoted on handle 16, the operation of the described latch release mechanism being obvious from the drawing.

In order that the clamp may be easily moved over table 10, I associate roller 31 with members 12 and 13. In the drawings, roller 31 is shown as carried by shaft 32 which is supported on member 13 by brackets 33. Preferably, the roller is so arranged that it clears table 10 when the under face of the clamp bears on said table, and so it lies in the vertical plane which bisects the angle between handles when the latter are spread apart sufficiently to clear members 12 and 13 from pipe 11. This is for the reason that the handles are ordinarily spread when the clamp, as a whole, is moved about the table.

Assume now that stand E has been attached to pipe 11 and that elevator D is in position at the top of the newly added stand. The string is picked up by the elevator sufficiently to take the weight off clamp A. The operator grasps the clamp handles, including release handle 30 within his grasp 115 to open the spring latch, spreads the handles apart to open the clamp, lifts up on the handle to bring roller 31 into engagement with the table and to clear members 12 and 13 therefrom and rolls the clamp forwardly 120 over the table (much after the manner of a wheel-barrow) to a position where it will not interfere with subsequent pipe handling operations.

In reapplying the clamp, it is drawn towards the pipe, (with members 12 and 13 at opposite sides thereof) and a single closing movement of the handles serves to swing the arcuate members into embracing association 125 with the pipe and to lock them in such 130

position. It then only remains to lower the string until the next pipe supporting shoulder comes to rest on shoulders 17.

From the above it will be evident that I have devised a simple, efficient pipe supporting means that greatly minimizes the labor required and time consumed in lowering and raising well pipe; but while I have shown a preferred embodiment of the invention, various changes in structure, design and arrangement may be made therein without departing from the scope of certain of the broader claims appended hereto.

Having described a preferred form of my invention, I claim:

1. In a device for suspending well pipe from rotary tables and the like, a plurality of arcuate members hinged together and adapted to embrace a pipe between them, upwardly facing supporting surfaces on the members, handles on and rigidly projecting from the members whereby they are adapted to be hingedly moved, a latch device on one of the members and adapted to cooperate with the other of said members to hold said members locked together, and latch control means on one of the handles and movable with relation thereto.
2. In a device for suspending well pipe from rotary tables and the like, a plurality of arcuate members hinged together and adapted to embrace a pipe between them, upwardly facing supporting surfaces on the members, handles on the members whereby they are adapted to be hingedly moved, an oscillatory latch device pivotally connected with one of said members and adapted to cooperate with the other of said members to hold said members in locked condition, spring means adapted to hold said latch device in operative condition, and means on one of said handles and operatively connected to said latching device for moving it out of operative position against the action of said spring.
3. In a device for suspending well pipe, the combination of a plurality of holding members hinged together and adapted to embrace the pipe between them, said members having upwardly facing supporting surfaces adapted to engage a downwardly facing shoulder on the pipe when said members embrace the pipe beneath said pipe shoulder, spaced handles on and rigidly projecting from the members whereby the members may be swung to and from pipe embracing position or bodily shifted, a latch device on one of the members and adapted to cooperate with the other of said members to hold said members in locked condition, and means on and movable with relation to one of the handles operable for moving the latch out of locking position.
4. In a device for suspending well pipe, the combination of a plurality of holding members hinged together and adapted to embrace the pipe between them, said members having upwardly facing supporting surfaces adapted to engage a downwardly facing shoulder on the pipe when said members embrace the pipe beneath said pipe shoulder, handles on the members whereby the members are adapted to be swung to and from pipe embracing position and whereby the device is adapted to be shifted bodily over the table when the members are out of pipe embracing position, a latch device on one of the members adapted to cooperate with the other of said members to hold said members in locked condition, means on one of the handles operable for moving the latch out of locking position, and a roller associated with one of the members and adapted to engage the table, the roller and said handles being so relatively arranged that vertical movement of the handles swings the members about the roller as a fulcrum and moves them vertically clear of the table.
5. In a device for suspending well pipe, the combination of a pair of pipe encircling members hingedly connected at one side, handles projecting from the other sides of the members whereby they may be opened and closed or lifted, said members having bottom surfaces adapted to rest on a supporting surface, and a roller mounted on one member at the side of the hinge removed from the handle, said roller being located above the plane of the bottom surfaces of the members so that when those members are resting on a supporting surface the roller will not engage the supporting surface, but that when the handle sides of the members are lifted and the members tipped said roller will engage the supporting surface.
6. In a device for suspending well pipe, the combination of a pair of pipe encircling members hingedly connected at one side, handles projecting from the other sides of the members whereby they may be opened and closed or lifted, said members having bottom surfaces adapted to rest on a supporting surface, and a roller mounted on one member at the side of the hinge removed from the handle, said roller being mounted on said member to rotate in a plane that is substantially central of the two members when opened.
7. In a device for suspending well pipe, the combination of a pair of pipe encircling members hingedly connected at one side, handles projecting from the other sides of the members whereby they may be opened and closed or lifted, said members having bottom surfaces adapted to rest on a supporting surface, and a roller mounted on one member at the side of the hinge removed from the handle, said roller being

members hinged together and adapted to embrace the pipe between them, said members having upwardly facing supporting surfaces adapted to engage a downwardly facing shoulder on the pipe when said members embrace the pipe beneath said pipe shoulder, handles on the members whereby the members are adapted to be swung to and from pipe embracing position and whereby the device is adapted to be shifted bodily over the table when the members are out of pipe embracing position, a latch device on one of the members adapted to cooperate with the other of said members to hold said members in locked condition, means on one of the handles operable for moving the latch out of locking position, and a roller associated with one of the members and adapted to engage the table, the roller and said handles being so relatively arranged that vertical movement of the handles swings the members about the roller as a fulcrum and moves them vertically clear of the table.

8. In a device for suspending well pipe, the combination of a pair of pipe encircling members hingedly connected at one side, handles projecting from the other sides of the members whereby they may be opened and closed or lifted, said members having bottom surfaces adapted to rest on a supporting surface, and a roller mounted on one member at the side of the hinge removed from the handle, said roller being located above the plane of the bottom surfaces of the members so that when those members are resting on a supporting surface the roller will not engage the supporting surface, but that when the handle sides of the members are lifted and the members tipped said roller will engage the supporting surface.

9. In a device for suspending well pipe, the combination of a pair of pipe encircling members hingedly connected at one side, handles projecting from the other sides of the members whereby they may be opened and closed or lifted, said members having bottom surfaces adapted to rest on a supporting surface, and a roller mounted on one member at the side of the hinge removed from the handle, said roller being mounted on said member to rotate in a plane that is substantially central of the two members when opened.

10. In a device for suspending well pipe, the combination of a pair of pipe encircling members hingedly connected at one side, handles projecting from the other sides of the members whereby they may be opened and closed or lifted, said members having bottom surfaces adapted to rest on a supporting surface, and a roller mounted on one member at the side of the hinge removed from the handle, said roller being

located above the plane of the bottom surfaces of the members so that when those members are resting on a supporting surface the roller will not engage the supporting surface, but that when the handle sides of the members are lifted and the members tipped said roller will engage the supporting surface, said roller being mounted on

said member to rotate in a plane that is substantially central of the two members when 10 opened.

In witness that I claim the foregoing I have hereunto subscribed my name this 30th day of September 1924.

ELIHU C. WILSON.
